C. B. PREISLER,
SELF RELEASING DAVIT BLOCK HOOK FOR LIFE BOATS,
APPLICATION FILED JULY 3, 1918.

1,297,300.

Patented Mar. 11, 1919.

Inventor:
Griswold B. Preisler
by J. Preisler Atty.

UNITED STATES PATENT OFFICE.

CRIST B. PREISLER, OF PORTLAND, OREGON.

SELF-RELEASING DAVIT-BLOCK HOOK FOR LIFE-BOATS.

1,297,300.

Specification of Letters Patent. Patented Mar. 11, 1919.

Application filed July 3, 1918. Serial No. 243,220.

To all whom it may concern:

Be it known that I, CRIST B. PREISLER, a citizen of the United States, and a resident of Portland, county of Multnomah, State of Oregon, have invented a certain new and useful Improvement in Self-Releasing Davit-Block Hooks for Life-Boats, of which the following is a specification.

My invention primarily relates to the 10 hooks of the fall-blocks of the tackle by which life-boats are suspended from davits.

The object of my invention is to provide a hook for the fall-block which shall automatically release itself from the rings of the 15 boat when the latter is afloat, but shall securely hold the boat until that moment. My invention also includes means for locking my hook, so that its automatic action will for the time being be suspended, which provision 20 renders my hook usable on pilot boats, and also for other uses where ordinarily the hook shall not be self releasing; and such lock also prevents the accidental opening of the hook.

25 My invention incidentally has for its object simplicity of construction.

The construction and operation of my device is clearly shown in the accompanying drawings, in which:

30 Figure 1 is a side elevation of my davit block hook by itself;

Fig. 2 is a corresponding end elevation; in these figures are also shown means for locking the hook against automatic opening and 35 releasing;

Fig. 3 shows my hook attached to one of the rings of the boat, of which a part is shown; this view also illustrates the actions due to the floating of the boat, causing the 40 automatic release of the hook from the rings of the boat; and

Fig. 4 shows the hook after having been automatically opened and having released the boat.

45 The main piece, *a*, of my hook has hinged to it a member, *b*, by hinge-rivet *c* extending through said member and the boss *d* of the main piece *a*. To the lower end of the member *b* is hinged, by a hinge-rivet *e*, a latch-bar *f*. The main piece, *a*, has a portion cut away so as to provide a recess *g*, in which to seat the transverse latch-pin *h* provided in a recess *i* of the latch-bar *f*. The member *b* is provided with a projecting, releasing lug 50 *k*. The life boat *n* is provided at each end with a ring or eye-bolt *m* as usual. Such

ring is provided with a link *j*, and this is fastened on the latch-bar *f* of my hook, as shown in Fig. 3. The main-piece, *a*, is made with an eye *p* which is connected by a link 60 *o* with the eye *p* of the band or shell of the fall-block, as shown in Fig. 3. *r*, *r'* represent parts of the rope bearing in the fall-block.

The self-releasing action of my hook is as 65 follows: When the latch-pin *h* is seated in the recess *g* of the main piece *a*, a downward pull on the link *j*, secured on the latch bar *f*, will have a tendency to retain the latter in its closed position. But when the 70 link *j* is subjected to an upward thrust it will abut against said releasing lug *k*, and in so doing rotate the member *b* to the right, with respect to the position of the parts in the drawings, and lift the latch bar *f* and 75 cause its latch-pin *h* to become unseated from the recess *g*, as shown in full lines in Fig. 3. The continued upward thrust of the link *j* would next cause the upper part thereof to 80 become wedged between the rounded extremity of the releasing lug *k*, and the latch bar *f*, forcing the latter outward, as shown in broken outline in Fig. 3, thus permitting gravity to act, and causing the latch-bar *f* to drop to its position in Fig. 4, with the 85 result that the link *j* would slide off and release the boat.

In Figs. 1 and 2 are also shown means for preventing the automatic opening of my hook, as described. As shown, these means 90 consist of a bolt *s* sliding in a bearing *t* fastened to the member *b*; and the main piece *a* is provided with a recess or locking cavity *u* into which the extremity of the bolt may be projected, as shown in Fig. 1. When so projected the upward thrust of the link *j* against the releasing lug *k* could have no effect, since any corresponding upward movement of the member *b* is prevented. It would be necessary first to withdraw the bolt *s* from the 95 cavity *u* in order to restore my hook to its self-releasing state.

The particular means disclosed by me for locking my hook so that it would temporarily not be self-releasing are to be understood as a mere suggestion, and these means may be varied as deemed convenient in the manufacture of my hook. And so, likewise, other details of construction may be varied as thought best. 105 110

I claim:

1. A hook of the character described com-

prising a main piece, a pendent member hinged thereto at one end, a latch bar hinged to the opposite end of said pendent member, the hinged end of said latch bar being adapted to have a link secured thereon, the pendent member having a releasing lug overlying said hinged end of the latch bar, and said main piece and the free end of said latch bar being provided with latching means adapted for being disengaged by the lifting of the latch-bar.

2. A hook of the character described comprising a main piece, a pendent member hinged thereto at one end, a latch bar hinged to the opposite end of said pendent member, the hinged end of said latch bar being adapted to have a link secured thereon, the pendent member having a releasing lug overlying said hinged end of the latch bar, said main piece and the free end of said latch bar being provided with latching means adapted for being disengaged by the lifting of the latch-bar, and means for locking the pendent member with the main piece.

3. A hook of the character described comprising a main piece, a pendent member hinged thereto at one end, a latch bar hinged to the opposite end of said pendent member, the hinged end of said latch bar being adapted to have a link secured thereon, the pendent member having a releasing lug overlying said hinged end of the latch bar, the extremity of said lug being so shaped that when the link secured on the latch bar is lifted it will tend to guide the former between the extremity of the lug and the latch bar, and said main piece and the free end of said latch bar being provided with latching means adapted for being disengaged by the lifting of the latch bar.

4. A hook of the character described comprising a main piece, a pendent member hinged thereto at one end, a latch bar hinged to the opposite end of said pendent member,

the hinged end of said latch bar being adapted to have a link secured thereto, the pendent member having a releasing lug overlying said hinged end of the latch bar, the extremity of said lug being so shaped that when the link secured on the latch bar is lifted it will tend to guide the former between the extremity of the lug and the latch bar, said main piece and the free end of said latch bar being provided with latching means adapted for being disengaged by the lifting of the latch bar, and means for locking the pendent member with the main piece.

5. A hook of the character described comprising a main piece, a pendent member hinged thereto at one end, a latch bar hinged to the opposite end of said pendent member, the hinged end of said latch bar being adapted to have a link secured thereon, the pendent member having a releasing lug overlying said hinged end of the latch bar, the extremity of said lug being so shaped that when the link secured on the latch bar is lifted it will tend to guide the former between the extremity of the lug and the latch bar, and said main piece and the free end of said latch bar being provided with interlocking tongue and groove and with latch pin and recess respectively.

6. A hook of the character described comprising a main piece, a pendent member hinged thereto at one end, a latch bar hinged to the opposite end of said pendent member, the hinged end of said latch bar being adapted to have a link secured thereon, the pendent member having a releasing lug overlying said hinged end of the latch bar, said main piece and the free end of said latch bar being provided with interlocking tongue and groove and with latch pin and recess respectively, and means for locking the pendent member with the main piece.

CRIST B. PREISLER.
